UNITED STATES PATENT OFFICE.

FRANK G. MCPHERSON, OF BEAVERFALLS, PENNSYLVANIA, ASSIGNOR
TO JOHN W. HOFFMAN, MONT D. YOUTES, AND J. FOSTER BELL, OF
ROCHESTER, PENNSYLVANIA.

SAVINGS-BANK.

SPECIFICATION forming part of Letters Patent No. 697,268, dated April 8, 1902.

Application filed November 19, 1901. Serial No. 82,833. (No model.)

To all whom it may concern:

Be it known that I, FRANK G. MCPHERSON, a citizen of the United States of America, residing at Beaverfalls, in the county of Beaver 5 and State of Pennsylvania, have invented certain new and useful Improvements in Savings-Banks, of which the following is a specification, reference being had therein to the accompanying drawings.

10 This invention relates to certain new and useful improvements in savings-banks, the primary object of the invention being to construct a bank of this character in which the savings may be deposited and from which 15 they cannot be removed except by the person or persons possessing the key to unlock the bank-door.

Many banks and savings institutions make a practice of issuing a small savings-bank to 20 depositors in which the savings are placed from time to time, the key to the savings-bank issued being retained by the depository issuing the bank, and my improved bank is particularly adapted for such use, though it 25 is as readily applicable to other uses.

Briefly described, the invention comprises a main receptacle or box provided with a suitable door, preferably secured by a lock requiring a key to open. This box or receptacle is 30 made substantially rectangular in shape, with the end having the door of greater area than the other end, for a purpose as will later be explained. This box or receptacle has a plate or false bottom placed therein adjacent to the 35 top of the box or receptacle, and in the space between this plate or false bottom and the top is placed a sliding plate, which is provided with an opening of a size sufficient to receive the largest coin. This sliding plate 40 is cut away at its forward end, so as to permit the same sliding sufficiently far into the box or receptacle to permit the discharge of the coin. This slot or cut-away portion in the sliding plate is guarded by a spring-held 45 gate that is actuated to be opened by the coin and which prevents the manipulation of the box or receptacle in any manner to reenter a coin into the sliding plate after having been deposited into the box or receptacle. All of 50 this construction and such other details as

enter into my invention will be hereinafter described in detail, and in describing the invention in detail reference will be had to the accompanying drawings, forming a part of my invention, and wherein like numerals of 55 reference will be employed to designate like parts throughout these several views, in which—

Figure 1 is a detail perspective view of my improved savings-bank. Fig. 2 is a longitudinal sectional view thereof. Fig. 3 is a transverse vertical sectional view. Fig. 4 is a detail perspective view of the spring-held gate removed from its position in the box or receptacle. Fig. 5 is a detail plan view of the sliding delivery-plate. 65

To put my invention into practice, I provide a substantially rectangular box or receptacle 1, which may be made from a suitable metal or other suitable material. This box or receptacle is made larger at one end 70 than at the other by having an offset portion 2, which is done in order that a gate may be suspended within the box or receptacle in such a position as to guard the delivery-slot and prevent the manipulating of the bank in 75 any manner to permit the removal of a coin or coins therefrom by unauthorized persons. A door 3 of any suitable form is placed in the box or receptacle, preferably in the larger end thereof, and this door may be provided 80 with any approved form of lock, preferably of a form employing a key to open or close the lock. The top 4 of the box or receptacle is cut away adjacent to the smaller end of the box, there being left, however, sufficient 85 material to form a flange 5 around three sides of the opening or cut-away portion 6. Placed within the box or receptacle 1 a slight distance below the top or cover 4 is a plate or false bottom 7, and in the space 8 between 90 this plate or false bottom 7 and the top or cover 4 there is fitted to slide neatly therein a coin-delivering plate 9. This plate 9 is provided with an opening 10, made at or about the center thereof and of a size sufficient to 95 receive the largest coins, the plate 9 being also slotted at its inner end, the slot 11 registering with the central opening 10. Cast or otherwise secured on the upright portion 12 of the top or cover are two lugs 14, and 100

jounaled in these lugs 14 is a shaft or spindle 14', which carries a gate or flap-valve 15, that lies normally in the slot 11. This gate or valve is held in this portion by means of 5 a spring, a practical form for which is shown in this illustration and consists of a wire wrapped around the shaft or spindle, with one end resting against the gate or valve and the other end resting against the top or cover. 10 This spring 16 has a tension only sufficient to normally retain the gate in the opening or slot in the sliding delivery-plate and is adapted to be overcome by the engagement of the coin with the gate, so as to cause the delivery 15 of the same when the box is tilted.

In operation the coin is placed in the opening 10 and the box or receptacle tilted, so as to cause the delivery-plate 9 to slide toward the larger end of the box or receptacle, carrying the coin therewith, until the latter comes into engagement with the spring-held gate, forcing the latter out of the way and permitting the coin to fall into the box or receptacle. Immediately upon the coin being 20 released the spring-gate returns to its normal position through the slot 11, which serves to allow the slide to be returned to its former position, thus closing the entrance from the box or receptacle to the opening 10 and preventing the removal of the coin other than 25 through the door when the latter is opened. I desire to call particular attention to the fact that in no position in which the sliding delivery-plate may be placed is there sufficient 30 room to permit the entrance of the smallest coin into the delivery-plate from the box or receptacle, thus absolutely preventing tampering with the contents of the bank. Upon retilting the bank, so that its smaller end will 35 be slightly below the level, the sliding delivery-plate will return to its normal position between the cover or top and plate or false bottom ready for the reception of another coin, and this sliding plate will readily remain in this position as long as the bank is in a level or substantially level position.

While the construction as herein shown and described is the preferred form of my invention, yet it will be observed that various 40 changes might be made in the details of construction—as, for instance, a different form of spring for the gate or constructing the box 45

or receptacle without the offset portion, and such changes as these may be made at will without departing from the general spirit of 55 the invention.

Having fully described my invention, what I claim as new, and desire to secure by Letters Patent, is—

1. In a savings-bank, a box or receptacle 60 partially cut away in the top or cover, a false bottom secured in the box a slight distance below top or cover, a coin-delivery plate arranged to slide longitudinally of the box within the space between the false bottom and the 65 top or cover, said plate having a coin-receiving opening and provided in one end with a slot communicating with the opening, a gate pivotally mounted in the box or receptacle, and a spring for normally holding said gate 70 in front of the space between the cover and the false bottom, substantially as described.

2. In a savings-bank, a box having a cut-away portion in the top thereof, a false bottom located within the box a slight distance 75 below the top, a spring-held gate pivotally mounted in the box and lying normally in front of the space between the top and false bottom, and a coin-delivery plate adapted to slide on the false bottom, said plate having a 80 coin-receiving opening and provided in one end with a slot which receives the gate when the box is tilted, as and for the purpose described.

3. In a savings-bank, a box or receptacle 85 having a portion of its top or cover cut away, a false bottom within the box or casing, and a spring-held gate which is normally held in front of the space between the top or cover and the false bottom, combined with a 90 slideable coin-delivery plate supported by the false bottom and having a coin-receiving opening and provided with a slot adapted to receive the gate when the box or receptacle is tilted whereby the gate is engaged by the coin and 95 operated to permit the discharge of the coin into the box or receptacle, substantially as described.

In testimony whereof I affix my signature in the presence of two witnesses.

FRANK G. MCPHERSON.
